UNITED STATES PATENT OFFICE

CECIL TURNER AND RAY TURNER, OF PETERSBURG, ILLINOIS

DESIGN FOR A FROZEN CUSTARD STAND

Application filed July 9, 1931. Serial No. 40,479. Term of patent 7 years.

To all whom it may concern:

Be it known that we, CECIL TURNER and RAY TURNER, citizens of the United States, and residents of Petersburg, in the county of Menard and State of Illinois, have invented a new, original, and ornamental Design for a Frozen Custard Stand, of which the following is the specification, and reference being had to the accompanying drawing, forming a part thereof.

The figure is a perspective of the frozen custard stand of our invention, disclosing the essential features of its design wherein the eaves of the roof are provided with ornamentalations representing icicles; with images of polar bears standing on their hind legs on the prominent corners of the roof; with an upright rectangular portion of the roof having its outer walls painted with a winter scene and the words "Frozen custard" painted over

the winter scene; with representations of icicles hanging over the top portion of the winter scene on each side of the wall; with the words "North Pole" and with poles prominently displayed at corners on the roof and supporting pennants thereon.

The four walls of the building are covered with composition plaster, substantially sprinkled with flaked mica.

There is a door in the rear of the building.

The two sides of the building are essentially alike in design. The ornamentation for the roof on the rear side of essentially like that on the sides of the roof.

We claim:

The ornamental design for a frozen custard stand as shown and described.

CECIL TURNER.
RAY TURNER.
